B. R. BENJAMIN.
CORN HARVESTER.
APPLICATION FILED MAY 7, 1914.

Patented July 17, 1917.

UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

CORN-HARVESTER.

1,233,303.

Specification of Letters Patent. Patented July 17, 1917.

Application filed May 7, 1914. Serial No. 836,852.

To all whom it may concern:

Be it known that I, BERT R. BENJAMIN, a citizen of the United States, residing at Oak Park, in the county of Cook and State of Illinois, have invented certain new and useful Improvements in Corn-Harvesters, of which the following is a full, clear, and exact specification.

My invention relates to corn harvesters. 10 It has heretofore been proposed to provide corn harvesters with bundle elevators adapted to receive the bundles discharged from the harvester and carry them away to a wagon or other receptacle following the binder in 15 the field. Difficulty has, however, been experienced with such elevators due to the fact that the conveyers thereon do not grip the bundles positively and feed them out promptly, an extra man being often required 20 to follow the machine and, when the conveyer combs through the stalks forming the bundle, start the bundle outward by shifting it into engagement with the conveyer.

My invention has for its object to improve 25 the construction of these conveyers in such a manner that the conveyer will grip the bundle discharged from the harvester as soon as it is discharged by the latter, the bundles being thereby carried away with increased 30 facility and celerity, and without any combing action of the conveyer or necessity for the starting of the bundle by the additional operator. I attain these objects by providing improved bundle elevating and convey- 35 ing mechanism so constructed that the moving element thereof engages the head of the bundle directly and is brought into more im- 40 mediate contact therewith throughout a sub- stantial length of the same in such a manner as to increase its bundle gripping capacity 45 and thereby increase its efficiency and ac- 50 celerate the delivery of the bundle.

In order that my invention may be fully and clearly disclosed, I have illustrated in 45 the accompanying drawing one embodiment which the same may assume in practice. In this drawing my invention is illustrated in connection with a corn binder and conveyer of standard construction, a rear elevation 50 of the same, partially in section, being shown.

The binder illustrated comprises a wheeled frame 1 carrying the usual binding mechanism 2 and discharging mechanism 3

operatively connected to the binder main 55 wheel 4 in a well-known manner and adapted to bind the corn into bundles and eject the same while in upright position rearwardly and stubblewardly between curved spring guides 5. As a bundle passes out 60 from between these guides 5 its butt passes off from the butt support 6 on the binder and it falls stubblewardly about its butt as a pivot onto a stubblewardly and upwardly disposed endless conveyer 7 having a series 65 of teeth or other suitable bundle gripping members 8 carried thereon and movable longitudinally of an elevator casing 9, the conveyer 7 being operatively connected to the binder mechanism through suitable power 70 connections 10, while the casing 9 is pivoted to the main frame at 11 at a point beneath the butt support 6.

In my improved construction the conveyer casing is provided with a peaked or 75 arched bottom 12 near its lower end, which reaches its maximum height at a point sub- 80 stantially opposite the lower end of the bundles as they fall on the conveyer after passing out between the arms 5, and from 85 that point, slopes away gradually toward the stubbleward end of the conveyer. By this construction it is to be noted that when a bundle falls in prostrate position upon the elevator, due to the arched bottom dis- 90 posed beneath the moving conveyer, the latter, since it must move over the peak on the bottom of the elevator, is brought into direct contact with the entire upper end of the bundle so that it may grip the bundle at 95 points along the length of the latter between its head and its center in such a manner as to positively carry it outward; in other words, the conveying mechanism is guided through such a path that it conforms sub- 100 stantially to the shape of the bundle as the latter is deposited upon the elevator, and its gripping members are thereby brought into direct contact with the bundle so that a more positive gripping action is obtained 105 which results in the bundle being fed forward positively and promptly upon its delivery to the elevator without any combing action on the part of the conveyer teeth or any tendency to break the ears from the 105 stalks.

While I have in this application described one form which my invention may assume in

practice, it is, of course, to be understood that the form shown herein is designed for purposes of illustration and that the invention may be embodied in other forms without departing from its spirit.

What I claim as my invention, and desire to secure by Letters Patent, is:

1. In combination, a binder, having discharge mechanism and a bundle elevator operatively connected to the binder for receiving bundles therefrom, said elevator having a raised portion near its lower end in a position relative to the binder discharge mechanism to receive the smallest part of the bundle when discharged from the binder whereby substantially the full length of the bundle is in contact with the elevator when the former is deposited upon the latter.
2. In combination, a binder having discharge mechanism, and a bundle elevator operatively connected to the binder for receiving bundles therefrom, said elevator having a peak in its bottom at a point intermediate its ends and positioned with respect to the discharge mechanism of the binder to engage the smallest part of a bundle de-

posited thereon when discharged from the binder.

3. In combination, a binder, and a bundle elevator operatively connected thereto for receiving bundles therefrom, said elevator intermediate its ends having a peak in the floor thereof positioned relative to the discharge portion of the binder for causing the head of a bundle to conform to the slope on one side of said peak when discharged from said binder.

4. In combination, a binder, and a bundle elevator including a stationary member raised intermediate its ends, and a traveling gripping member, the raised portion of the stationary member being positioned to receive directly bundles discharged from said binder with their heads on one slope of said raised portion to insure a secure gripping thereof by said gripping member.

In testimony whereof I affix my signature, in the presence of two witnesses.

BERT R. BENJAMIN.
